UNITED STATES PATENT OFFICE.

FRANK L. LATHROP AND HARRY C. H. WALSH, OF BROOKLYN, ASSIGNEES
TO H. L. JUDD & CO., OF NEW YORK, N. Y.

RING.

SPECIFICATION forming part of Letters Patent No. 541,974, dated July 2, 1895.

Application filed May 2, 1895. Serial No. 547,839. (No model.)

To all whom it may concern:

Be it known that we, FRANK L. LATHROP and HARRY C. H. WALSH, residents of Brooklyn, Kings county, State of New York, have 5 invented certain new and useful Improvements in Rings, of which the following is a specification.

Our invention relates to rings, especially designed for use as curtain rings.

10 Our invention is mainly directed to the mode of fastening a roller or rollers to the ring to enable the ring to traverse on a certain pole.

To this end our invention consists in the 15 construction hereinafter set forth and claimed.

In the drawings, Figure 1 is a blank of the roller-supporting frame. Fig. 2 is a side view of the roller mounted in its supporting frame. Fig. 3 is an edge view of the roller shown in

20 Fig. 2. Fig. 4 is a detail view of a ring, showing the rollers in place; and Fig. 5 is an enlarged sectional detail view on line 5 5 of Fig. 4.

Referring particularly to Fig. 1 it will be 5 noted that the blank consists of cheeks *a a*, each of which terminates in a guard *b b* and are united one to another by a bridge *c* from which clips *d d* project. This blank is bent up into the form shown in Figs. 2 and 3—that 30 is to say, the cheeks are bent away from the bridge in one direction at right angles, and in substantial parallelism the clips *d d* are likewise bent away from the bridge at right angles, but in the opposite direction, the said clips standing at right angles to the planes of the cheeks, as shown. The guards *b b* are bent away from the planes of the cheeks *a a* laterally at right angles and are curved to cover the raw edges of the opening in the ring, as 35 40 will be more fully set forth.

Extending through the supporting frame

from cheek to cheek is an axle or gib *f* upon which is carried a roller or rollers *g*.

A is the ring which is hollow in the usual form of sheet metal rings.

45 The roller and its supporting frame are mounted in the ring as follows: The ring is cut away or apertured as at *h* and preferably slightly bent or flattened as at *i*, which flattened portion is pierced by apertures *j j*. The 50 roller and its supporting frame are inserted into the slot or opening *h*, the clips *d* being inserted through the holes *j j* and bent down or clinched, as shown in Figs. 4 and 5, thus forming a secure fastening for holding the 55 supporting frame and roller in the ring, the guards *b b* serving to cover the raw edges of the slot *h*.

What we claim, and desire to secure by Letters Patent, is—

60 1. The combination of a ring *A*, a roller and a supporting frame therefor consisting of substantially parallel cheeks *a a*, guards *b b*, extending laterally therefrom, a bridge *c* uniting the cheeks and clips *d d* projecting 65 from the bridge and adapted to pass through holes *j j* in said ring *A*, substantially as described.

2. The combination of a ring, a roller supported therein by a frame, the said supporting frame consisting of a bent up sheet metal blank comprising substantially parallel cheeks *a a*, curved guards *b b* projecting laterally from the ends of the cheeks, clips *d d* adapted to pass through holes *j j* and a bridge 70 75 *c* uniting the cheeks and the clips, substantially as described.

FRANK L. LATHROP.

HARRY C. H. WALSH.
